UNITED STATES PATENT OFFICE.

BENJAMIN F. HEIMBACH, OF ALLENTOWN, PENNSYLVANIA.

DESIGN FOR BURIAL-CASE.

Specification forming part of Design No. 6,772, dated July 15, 1873; application filed April 25, 1873.

To all whom it may concern:

Be it known that I, BENJAMIN F. HEIMBACH, of Allentown, Lehigh county, Pennsylvania, have invented a Design for Burial-Caskets, of which the following is a specification:

My improved design for burial-caskets consists in the shape I give to the ends, which are in the form of a half-hexagon and beveled, and the bevel of the sides, together with the style of ornamentation adopted in the moldings, cover, ends, and sides.

That the character of my invention may be more easily understood, I will proceed to describe the same, having reference to the drawings, in which like letters of reference indicate like parts.

In the accompanying drawings, *a* is a side view of the body of the casket, showing bevel and silver-plated molding, half-round bead *b*, with nails to match. *C* shows the shape of the ends, each end being in the shape of a half-hexagon, and beveled, with three plane surfaces with silver-plated molding, half-round bead *d* running round each surface. *E* shows the lid, the ends of which are cut off,

so as to give each the shape of a half-hexagon. The raised part of the lid is molded, the members of which are an ogee, *f*, a fillet, *g*, and cove *h*. *I* is a slide or cover over glass panel in lid, one end conforming to the shape of the lid, the other end being half-round, with cove *h* in edge, turning on silver plated screw *l*, and fastened at the other end by two silver-plated screws. Ends put together by a miter.

What I claim as new is—

The within-described design for coffins, in which the ends are semi-hexagonal, inclining outward from the bottom, and each face thereof, as also the sides of the coffin, occupied by a panel of half-round molding, the whole surmounted by a lid half the depth (slightly more or less) of the box, and composed of a combination of molding, substantially as shown.

In testimony whereof I have signed my name to this specification before two subscribing witnesses.

B. F. HEIMBACH.
